UNITED STATES PATENT OFFICE.

GEORGE H. DRYDEN, OF BALTIMORE, MARYLAND.

LIGHTNING-ARRESTER.

1,359,971.

Specification of Letters Patent. Patented Nov. 23, 1920.

Application filed September 10, 1914. Serial No. 861,125.

To all whom it may concern:

Be it known that I, GEORGE H. DRYDEN, a citizen of the United States, residing at Baltimore city and State of Maryland, have invented certain new and useful Improvements in Lightning-Arresters; and I do hereby declare the following to be a full, clear, and exact description of the invention, such as will enable others skilled in the art to which it appertains to make and use the same.

The invention relates to improvements in the type of arresters in which the electrodes are maintained in a vacuum, and the object in view is increased efficiency.

In the drawings,—

Figure 1 is a perspective view of an arrester embodying the features of the present invention.

Fig. 2 is a longitudinal, vertical section through the arrester cartridge detached.

Fig. 3 is a transverse, vertical section taken on the plane indicated by line 3—3 of Fig. 2, and looking in the direction indicated by the arrow.

Fig. 4 is a view similar to Fig. 2 of a modified embodiment.

Fig. 5 is a perspective view of a knife fuse detached adapted to be substituted for the knife switch seen in Fig. 1.

Fig. 6 is a diagrammatic showing of a form of connection for the arrester.

Referring to the drawings by numerals, 1 indicates a base, which, though illustrated in a horizontal position, is adapted to be disposed vertically in use. Fixed to and outstanding from base 1 are the clips 2, 2, of a knife switch 3, the clips being connected respectively to binding posts 4 and 5. If preferred, a knife fuse 6 may be substituted for knife switch 3. Clips 7 and 8 outstand from base 1, the former clip being connected with binding post 5 and one of the clips 2, and clip 8 being connected with a binding post 9. Between the clips 7 and 8 is arranged the arrester cartridge A whose axially projecting terminals are mounted respectively in the clips 7 and 8.

The cartridge A consists of a tubular cylinder 10 of appropriate substance, being of metal in the embodiment seen in Fig. 1. Within the cylinder 10 are arranged terminal stoppers 11, 11, of air tight insulating material, each backed by and held against axial displacement by a terminal insulating

disk 12 fitted within the respective end portion of the cylinder 10 and held in place therein by the respective end portions of the cylinder being crimped or spun to form an inwardly extending flange 10' lapping and surrounding the periphery of the respective disk 12. Terminals 13, 13, preferably of metal, have their inner ends embedded in the insulations 11, and each of said terminals has its inner end fixed to a non-fusing conductor 14 projecting axially inwardly from the respective terminal and connected thereto as by a screw or bolt 15 extending through the respective terminal and its engaged conductor 14. The non-fusing conductors 14 may consist of carbon, graphite or the like, and extend inwardly toward each other with their inner ends spaced apart an appropriate distance for forming such a spark gap as can be readily jumped by a static charge but which will afford effective insulation for currents of ordinary usable potential. Each conductor 14 in extending from its terminal 13 projects through an insulator block 16, of glass, porcelain, or other appropriate insulating material, each of which is cylindrical in form and provided with an annular recess 16' surrounding the respective conductor 14 for a portion of its length so as to form a cup or receptacle for disintegrated material which is liable to fall from the conductors due to constant arcing between the electrodes, the said conductors 14 comprising two of the electrodes of the arrester. The insulators 16 are spaced apart axially by an interposed tube 17 snugly fitted within cylinder 10, and surrounding and being spaced from the two electrodes 14 a distance equal to the distance between said electrodes, the tube 17 being a conductor of the same substance as electrodes 14 and comprising the third electrode of the arrester. The distance being the same between any one of the electrodes and any other one, it is obvious that if a static charge discharges from one electrode to another alone the result will be due to conditions beyond the arrester, and that conditions being uniform the discharge will take place between an electrode and the other two electrodes, the discharge being thus divided. A binding post 18 is connected to cylinder 10 for the ground wire of the arrester. As the electrode 17 discharges through binding post 18, said electrode may be considered the ground electrode, while 110

the other two electrodes being connected to line are the line electrodes and consequently the shunt electrodes.

As seen in Fig. 6, one application of the 5 arrester consists in connecting binding post 4 to line, while binding post 5 is connected to the receiving instrument 19, and the other side of the instrument is connected to line, the latter line having a branch 20 connected 10 with binding post 9. Thus the normal current is not carried through cartridge A, there being no electrical connection for the working current through the cartridge, but instead current is carried from binding post 15 5 to instrument 19, to the return line of the instrument. If either line becomes statically charged, such charge will not approach instrument 19, but will enter cartridge A either from binding post 5 or through 20 branch 20 and binding post 9. The charge finding its way along one of the electrodes 14 usually divides and discharges in part to the other electrode 14 and in part to electrode 17, the discharge to electrode 14 being 25 neutralized by an induced charge in the line with which said electrode is connected, and the discharge to electrode 17 being grounded.

In the course of manufacture of the cartridge, vacuum is produced therein in any 30 well known manner, and the insulators 15 coöperat with cylinder 10 for maintaining the vacuum, so that electrodes 14 and 17 are exposed in a vacuum, the electrode 17 serving also as a heat insulator for preventing 35 cylinder 10 from becoming heated with resulting liability of expansion and loss of vacuum.

It is apparent that in operation the improved arrester provides for a combination 40 of shunt and ground within a vacuum which will effectively dispose of static charges with the least possible resistance so as to afford maximum efficiency in protecting instruments in line without liability of variation 45 in the action of the working current.

In Fig. 4 is illustrated an embodiment of the invention adapted to enable visual inspection of the arc resulting from static discharge. In this structure the parts are identical in form and operation with those of the structure above described with the exception of the slight alterations necessary 50 for rendering the electrodes visible. Specifically, the structure consists of a transparent, preferably glass cylinder 21, to the ends of which are externally threaded caps 22 of metal and within which are arranged the air tight insulators 23, 23, engaged by the cup insulators 24. Between the insulators 24 55 is arranged the cylindrical electrode 25 which is connected by conductor 26 with the cap 22 at one end, the said cap being engaged by the ground binding post 27. The axially extending electrodes 28, 28, are 60 spaced within electrode 25, a vacuum being 65

formed and maintained in such space. Each electrode 28 connects with its respective axial terminal 29 which projects through the respective end of the cartridge and is adapted to engage a clip 7 or 8 of the form 70 of base seen in Fig. 1. Electrode 25 is formed with an aperture 25' extending radially from cylinder 21 to the space between electrode 25 and electrodes 28, the aperture 25' being also in line with the gap between 75 electrodes 28, so that any arcing occurring within the cartridge will be visible through the aperture 25'. Otherwise the structure operates exactly the same as cartridge A. Of course, each cap 22 has a central aperture surrounding the respective terminals 29 of sufficient diameter to insure a greater resistance to the passage of electricity from the terminal to the cap than the resistance of the gap between electrodes. 85

Either the knife 3 or the fuse knife 6, as will be apparent, may be used for testing purposes.

What I claim is:—

1. An electric signaling circuit comprising 90 an instrument to be protected from excess voltage, a vacuum chamber, two spaced shunt electrodes therein, connected to said circuit on either side of said instrument, a ground electrode also located in said vacuum chamber, and spaced from each of said shunt electrodes so that three gaps are provided, said gaps being so proportioned to the impedance in the line circuit and in the line to ground as to secure a division of excess voltage current. 95

2. An electric signaling system comprising 100 a device to be protected from excess voltage, a vacuum chamber, two spaced shunt electrodes therein, a ground electrode 105 also located in the vacuum chamber, and so placed that the shortest distance between it and each of the shunt electrodes is the same as the shortest distance between the two shunt electrodes, the line beyond the vacuum 110 chamber being without gap or substantial reactance.

3. In an arrester, a plurality of electrodes, a transparent tube surrounding said electrodes and a heat insulator within the 115 tube surrounding said electrodes.

4. In an arrester, a plurality of electrodes, a transparent tube surrounding said electrodes, and a heat insulator encircling one 120 of said electrodes.

5. In an arrester, a plurality of electrodes, a transparent tube surrounding said electrodes, and a heat insulator surrounding said electrodes but permitting observation 125 of same.

6. In an arrester, a plurality of electrodes, a transparent tube surrounding said electrodes and providing a vacuum chamber, and a heat insulator surrounding said electrodes but permitting observation of same. 130

7. In an arrester, the combination with a tubular cylindrical casing, of an insulator in each end portion of the casing having a hermetical engagement therewith, an insulator 5 cup engaging each of said insulators, the cups being spaced apart axially of the casing, a tubular electrode disposed between and engaging the cups, a terminal disposed externally of the casing and electrically connected with said electrode, axially disposed electrodes extending within the first-mentioned electrode and spaced therefrom and spaced apart a distance substantially equal to the distance between the first-mentioned 10 electrode and the second-mentioned electrodes, such distance being sufficiently short to enable arcing, and terminals for the second-mentioned electrodes projecting axially from within the tubular casing.
8. An electric signaling system comprising a device to be protected from excess voltage, a transparent tube containing a vacuum, a plurality of electrodes therein arranged substantially parallel to the axis of 15 the tube, a third electrode within the tube so placed that the shortest distance between the third electrode and each of the other electrodes is the same as the shortest distance between any two of the first-mentioned electrodes, the line beyond the vacuum tube being without gap or substantial reactance.
9. An electric signaling system comprising a device to be protected from excess voltage, a transparent vacuum chamber, three electrodes therein so spaced that the shortest distance between any two of said electrodes is uniform, line connections to two of said electrodes and from said electrodes to the coil to be protected, and a ground connection to the third electrode, whereby any high frequency discharge capable of passing between any of the electrodes will be subdivided and will partly pass to ground, the line beyond the vacuum chamber being without gap or substantial reactance. 35 40 45
10. An electric signaling system comprising a device to be protected from excess voltage, a vacuum chamber, a plurality of axially aligned spaced shunt electrodes therein, a tubular ground electrode surrounding the spaced electrodes and spaced therefrom the same distance as the shunt electrodes are spaced apart, the line beyond the vacuum chamber being without gap or substantial reactance. 50 55
11. The device of claim 10 characterized by the provision of means permitting a view of the space between the shunt electrodes.
